[57] **CLAIM**

The ornamental design for an enclosure for nail clipper, as shown and described.

DESCRIPTION

FIG. 1 is a top perspective view of an enclosure for nail clipper showing my new design;

FIG. 2 is a bottom perspective view thereof;

FIG. 3 is a left side elevational view thereof, the right side being a mirror image;

FIG. 4 is a front elevational view thereof; and

FIG. 5 is another top perspective view thereof, with a nail clipper shown in broken lines for illustrative purposes.
